UNITED STATES PATENT OFFICE.

GEORGE FERGUSON, OF WOLLASTON, MASSACHUSETTS, ASSIGNOR TO UNITED SHOE MACHINERY CORPORATION, OF PATERSON, NEW JERSEY, A CORPORATION OF NEW JERSEY.

SHOE SOLE.

1,425,517.

Specification of Letters Patent. Patented Aug. 15, 1922.

Application filed December 13, 1918. Serial No. 266,578.

To all whom it may concern:

Be it known that I, GEORGE FERGUSON, a citizen of the United States, and resident of Wollaston, in the county of Norfolk and 5 State of Massachusetts, have invented certain Improvements in Shoe Soles, of which the following description, in connection with the accompanying drawings, is a specification, like reference characters on the 10 drawings indicating like parts in the several figures.

The present invention relates to the manufacture of shoes and more especially it concerns the manufacture of shoes of the kind 15 in which the shoe upper is sewed, while reversed or inside out, to a single sole and the shoe thereafter turned right side out, such shoes being commonly termed "turn" shoes.

By way of illustration the invention is 20 herein shown in its application to the manufacture of turn shoes with molded and vulcanized rubber compound soles of the type shown and described in Patent No. 1,286,176, granted November 26, 1918, on an application 25 filed in my name. It is to be understood, however, that the invention is not intended to be limited thereby, but to be applicable to the manufacture of any character of shoes in which the invention may be 30 used to advantage.

The invention has for its principal object to improve the manufacture of turn shoes, particularly with respect to the construction and formation of the soles and the manner 35 of assembling the sole and constituent parts of the shoe so as to reduce the production cost of the shoes and improve their serviceability and comfort.

With this object in mind the invention 40 contemplates a rubber compound sole constructed to be incorporated in a turn shoe as the outer tread member of the shoe and having a marginal portion and a central foot-supporting portion, said sole being 45 molded to form, adjacent to the feather, an outwardly facing sewing shoulder the top of which is in substantially the plane of said central portion, and a stitch-receiving gutter separating the sewing shoulder from the 50 central portion of the sole. In the illustrated embodiment of the invention the sole comprises a sole-shaped body of rubber compound and an upper layer of textile material the marginal portion of which is projected upwardly with the rubber body to 55 provide a sewing rib and the portion of the

sole within the sewing rib is built up to substantially the height of this sewing rib so as to form a substantially level foot-engaging surface for the sole. The built up central 60 portion of the sole is separated from the sewing rib by a narrow gutter the function of which is to provide the necessary clearance for the needle in sewing a shoe upper to the sole and to receive the inseam stitches. 65 As herein shown the central portion of the sole is built up by applying to the sole a layer or layers of fabric shaped to extend to the inner edge of the gutter and preferably disposed between the rubber body and the 70 rib forming layer. This built-up fabric portion of the sole not only gives the sole more body and strength but it also serves as an insulation for the foot, both of which features are of especial importance in a turn 75 shoe wherein only the single sole is employed.

The invention further contemplates a sole for turn shoes made of composite material and having a sewing rib or shoulder formed 80 along its marginal surface with the top of the shoulder substantially flush with the upper surface of the sole through the forepart of the sole and having a recess formed in the upper surface of the shank portion of 85 the sole within the shoulder adapted to receive a shank stiffening member. This is herein accomplished by projecting the sewing rib a uniform height above the upper surface of the sole and terminating the 90 built-up portion of the sole at substantially its ball line whereby the sewing rib along either side of the shank of the sole together with the rear end of the built-up portion of the sole produces the walled stiffener receiving recess for the shank and if desired the 95 heel seat portion of the sole.

The composite turn sole thus produced is employed, in the illustrated preferred practice of the invention, by a procedure which 100 comprises assembling the sole and the shoe upper inside out upon a last and sewing the upper to the sewing rib of the sole, turning the shoe right side out while the sole is flexible in the shank, arranging in the prepared 105 recess a shank stiffening member the upper surface of which is substantially flush with the top of the adjacent sewing rib and the forepart of the sole and thereafter relasting the shoe and completing its manufacture in 110 the usual manner. It will be noted that the shank stiffener receiving recess enables the

stiffening member accurately to be incorporated in the shoe and maintained in position most efficiently to perform its functions without additional fastening means.

- 5 In its preferred practice, the invention further contemplates the application of a filling material to the stitch receiving gutter formed on the upper surface of the sole prior to turning the shoe right side out and advantageously while the sole is in its reversed conformation on the last in which case the filler material is held in place in the gutter under compression when the sole resumes its normal conformation in the finished shoe.
- 10 15 The shoe bottom gutter filler provided by the invention and illustrated herein comprises a strip of conformable and preferably slightly compressible material of indefinite length and of a cross-sectional shape to fill the stitch receiving gutter of the sole substantially flush with the adjacent surfaces of the sole. By applying this filler strip to the sole when it is still attached to the first last, as directly after the sewing operation, the 20 25 gutter is opened up or "sprung" because of the reverse convexity of the sole which facilitates the application of the filler in the gutter and subsequently when the shoe is removed from the last and turned right side out the gutter closes in on the filler strip and acts to hold it under compression, the compressibility of the material also compensating for any variation in the shape of the filler which would interfere with the 30 35 desired conformation of the sole. The feature of the invention which provides a shoe bottom gutter filler and the application of this filler to the stitch-receiving gutter after the sewing operation is performed on the 40 45 shoe to present a surface flush with the top of the sewing rib and the central surface of the sole is applicable also to the manufacture of welt shoes in which the insole is made so as to provide a sewing rib substantially flush with the surface of the insole within the sewing rib, the gutter filler leveling off the bottom of the insole and providing a flat surface upon which to lay the outsole.
- 50 55 The term "rubber" is herein used to designate rubber, rubber composition, and similar composite materials including the so-called "fibre" sole compositions now extensively used.
- 60 65 The invention will now be described in connection with the accompanying drawings which illustrate a preferred embodiment of the invention and the invention will then be pointed out in the appended claims.
- 65 In the drawings,—
- Fig. 1 is a perspective view of a sole for turn shoes made in accordance with a preferred embodiment of the invention, the sole being shown partly in transverse section at the forepart;

Fig. 2 is a perspective view showing the shoe upper attached to the sole and the manner of filling the stitch receiving gutter of the sole;

Fig. 3 illustrates the application of a shank stiffening member to the sole in accordance with the preferred practice of the invention;

Fig. 4 is a view, partly in section, of the completed shoe.

In manufacturing a rubber turn sole such as herein illustrated for the purpose of explaining the invention, a composite sole structure is built up from a sole-shaped body 2 of rubber compound and a top layer 4 of fibrous material such as heavy canvas, the rubber body being of substantially uniform thickness and of unvulcanized rubber stock. The top layer 4 of canvas, the marginal portion of which is to co-operate with the rubber body 2 in producing the inseam stitch receiving structure or sewing rib for the sole is cut out to a size to cover substantially the entire upper surface of the body 2 as shown. The material which is to build up the central portion of the sole blank within the sewing rib is herein shown as consisting of two layers 6, 8 of canvas of a size and thickness to cover the central portion of the sole blank within the sewing rib and provide a surface for this portion of the sole which is substantially the same height as the top of the sewing rib. These filler layers, 6, 8, as shown in the drawings, preferably terminate at substantially the forward end 90 of the shank portion of the sole blank for a purpose hereinafter to be explained and are interposed between the top layer 4 of canvas and the rubber body 2. Also the blank of filler material is slightly smaller than the 95 area within the sewing rib and is centrally disposed on the blank so that the edges of the two layers will present an upright wall forming the inner wall of the gutter which is molded in the upper surface of the sole. 100 Although the kind of material used to constitute the filler for the sole is not essential canvas material has given very satisfactory results since it is adapted to become effectively consolidated with the rubber body of the sole by vulcanization and serves to reinforce the sole and add to its wearing qualities. It is not necessary to interpose the filling layers 6, 8 between the rubber body and the top layer but they may be advantageously molded on top of the layer 4 of the sole or the central portion of the sole may be composed entirely of the material of which the sole is made. In this case, however, the utility of the canvas material as an 115 insulator for the foot in the interior of the shoe is not obtained.

After the layers which are to constitute the composite sole have been accurately assembled they are carefully placed between 120

two co-operating sole molds and subjected to a molding pressure and to vulcanization. The sole shaping faces of these molds are formed and arranged to mold along the upper 5 marginal surface of the sole blank a predetermined distance in from its sole edge an outwardly facing sewing shoulder 12 against which the shoe upper is to be sewed, and a feather 14 extending outwardly from the base of the shoulder and forming the sole margin. Preferably the sewing shoulder or rib 12 is formed in the mold by uniformly reducing the thickness of the sole material along its margin in order that the 10 sewing rib may be of a uniform height relatively to both the tread and to the upper surfaces of the sole with its top in substantially the plane of the central foot supporting portion in the completed shoe. An 15 inseam stitch receiving gutter 16 is also molded in the upper surface of the sole blank a predetermined distance inwardly from the shoulder and extending parallel to the said shoulder with the bottom of the 20 gutter opposite the base of the sewing rib 12 to provide the required "between substance" 20 to hold the inseam stitches. The inner wall 22 of this gutter is formed primarily by the edges of the canvas layers 6 25 and 8 which constitute the central portion 24 of the sole and the upper surface of this central portion 24 is so molded that it lies in substantially the plane of the top of the sewing rib 12 thus providing a substantially 30 level upper surface for the sole from shoulder to shoulder. The gutter 16 separating the shoulder 12 and the main foot supporting portion 24 of the sole is only sufficiently 35 wide to give the proper clearance for the 40 sewing needle as it emerges from the inner wall of the sewing rib during the shoe upper attaching operation.

The sole illustrated is intended for use with the so-called "sewed seat" turn shoe 45 and accordingly the sewing rib 12 extends entirely around the heel end of the sole and it projects a uniform height above laterally adjacent surfaces (the feather and the bottom of the gutter) of the sole throughout 50 the shank, the heel seat and the forepart of the sole. As shown in the drawings the upper surface of the sole within the sewing rib throughout the shank and heel seat of the sole is molded so as to lie in a plane 55 substantially lower than the plane of the upper surface of the sole portion 24 in the forepart and the top of the sewing rib 12. By reason of the projecting rib and the 60 termination of the built-up portion of the sole at the forepart a walled recess 26 is thus formed in the upper side of the shank and heel seat of the sole. The purpose of 65 this recess is to receive the shank stiffening member most advantageously as a constituent part of the shoe and more especially

with its upper surface flush with the top of the sewing rib 12 and the central portion 24 of the sole. It is to be appreciated, however, that the formation and arrangement of the stiffener receiving recess may be 70 varied within the scope of the invention according to the character of the shank stiffening member intended to be employed. By reason of the molding and vulcanization of the canvas layers 4, 6 and 8 and the rubber body 2 they become consolidated and firmly vulcanized together, the additional fabric layers 6 and 8 incorporated in the forepart of the sole adding appreciably to the body and strength of the sole while the 75 shank portion of the sole particularly with the prepared recess 26 remains sufficiently flexible to permit it readily to be turned during the manufacture of the shoe.

In the practice of the invention with the 80 sole so constructed a shoe upper 28, together with the sole, is first assembled on a last 30 and the shoe upper attached to the sewing rib 12 of the sole by the stitches 32 in the customary manner as shown in Fig. 2, 85 the stitches being received in the gutter 16 formed on the upper surface of the sole. It will be seen from Fig. 2 that the bottom of the last 30 is slightly convexed transversely and thus when the sole is tacked on 90 to the last bottom the margin of the sole is inclined in a manner to facilitate the lasting and the sewing of the upper to the rib 12. This inclination of the sole margin by reason of the shape of the last bottom 95 and also the tension of the inseam stitches 32 on the sewing rib further acts to open up or enlarge the gutter which facilitates the subsequent filling of the gutter. As illustrated in Fig. 2 the needle of the sewing 100 machine passes through the between substance 20 of the rib 12 and emerges on the inner side in such manner, by reason of the gutter 16, that the stitches are drawn against the inner wall of the rib. Since the 105 bottom of the gutter is opposite the base of the sewing shoulder adjacent to the feather 14 of the sole, it is possible to attach the upper with a short and therefore a strong stitch which is particularly desirable in a 110 turn shoe as the entire strength of the shoe is dependent upon it. Also the stitches, by being located in the gutter, can not engage the foot and may be readily concealed.

In order to provide a substantially continuous foot engaging surface for the sole in substantially a single plane throughout the forepart, the gutter 16 is filled flush with the top of the adjacent sewing rib 12 and the surface of the central portion 24 of the 115 sole. Preferably this gutter is filled at this stage in the process of making the shoe, that is directly after the sewing operation, and for this purpose a strip of filling material 120 such as illustrated in Fig. 3 of the draw- 130

ings is conveniently used. This filler material 34 consists of a strip of flexible and slightly compressible material of indefinite length and of a cross-sectional shape to fill 5 up the gutter 16. A strip of inexpensive vulcanized rubber compound has been found suitable for this purpose as such material is readily conformable to the gutter and slightly compressible for a purpose hereinafter to 10 be mentioned. Moreover the filler material is sufficiently flexible to fill the gutter without interfering with the subsequent flexing of the sole during the operation of turning the shoe right side out. The filler is laid 15 along the gutter during this step of the process as illustrated in Fig. 2. It is desirable, however, that the filler material should not fit too snugly within the gutter since the gutter is enlarged when the sole is 20 on the last and this would tend to keep the gutter opened and interfere with the sole assuming the desired reverse convexity when relasted. Under ordinary conditions it will not be found necessary to apply the filler 25 with cement as the gripping of the filler between the upright walls of the gutter when the shoe is turned inside out will be sufficient to hold the filler securely. While a strip of previously prepared filler material 30 is herein shown as used to fill the gutter, it is to be understood that it is also within the scope of the invention to fill the gutter in a different manner, as for example, by using a suitable plastic composition to fill the 35 gutter or by applying the filler after turning the shoe right side out.

In the next step in the manufacture of the shoe it is removed from the last 30 and turned inside out, the central portion 24 of 40 the sole not interfering with the turning of the shoe in the customary manner while the recess shank portion 26 of the sole permits the shoe to be flexed very readily. A shank stiffening member is next arranged in the 45 shank receiving recess 26 on the upper side of the sole. The shank stiffening member which is universally used in the manufacture of turn shoes, consists of a leatherboard or fibreboard member 36 shaped to occupy 50 the heel seat area of the shoe and extend forwardly through the shank of the shoe within the sewing rib to substantially the ball line, the underside of this member having a narrow strip of tempered steel 37 attached to 55 it to reinforce the fibreboard. In accordance with this invention this fibreboard shank piece 36 is shaped to fill up the recess 60 26 formed by the sewing rib and the upper surface of the sole through the shank and heel seat, the stiffener being of sufficient length to butt against the shoulder formed by the termination of the built-up forepart portion 24 at the ball line and of a thickness to provide a continuation of the foot 65 engaging surface of the sole at the forepart

rearwardly to the heel seat. By placing the shank stiffening member 36 in the prepared recess 26, its location relatively to the sole is readily and accurately determined and it is held in such position by the sewing rib 70 12 so that it can not be displaced thereon either during further operations on the shoe or the wear of the shoe. This shank piece 36 serves to stiffen the longitudinally arched shank portion of the sole and to provide 75 support for the arched portion of the foot. In "nailed seat" turn shoes this stiffener constitutes the connection between the shoe upper around the heel end and the sole, but this latter function of the shank stiffening member has no utility herein inasmuch as a 80 sewed seat shoe is illustrated. After the shank stiffening member is placed in the recess prepared for it in the sole the shoe is relasted and thereafter the operations necessary to complete its manufacture are performed in the usual manner. The relasting of the shoe or more strictly the removal of the shoe from the first last enables the sole to return to its normal conformation and 85 particularly its transverse conformation so that the gutter 16 tends to close up and thereby grip the filler strip 34 between the inner wall of the sewing rib 12 and the opposed wall 22 of the gutter. Where the filler material which is used is slightly compressible any slight variation either in the cross-sectional shape of the filler or the shape of the gutter may be readily compensated for when the shoe is second lasted without distorting or otherwise injuring the desired 90 smooth tread surface for the sole.

Since the foot engaging surface of the sole is substantially level from rib to rib, transversely, and also throughout the entire 105 length of the sole, there is no need for a separate filler piece such as it is now essential to use in turn shoes thus eliminating the labor and expense involved in leveling off the interior foot engaging surface of the sole. In 110 fact it is entirely practical to apply the usual turn shoe sock lining 40 to the upper side of the sole without further operation upon the interior of the shoe as illustrated in Fig. 4. It will be recognized that the sole and the 115 procedure by which it is incorporated in a shoe as herein described makes it possible to produce a comfortable and serviceable shoe with a minimum number of shoemaking operations and a relatively small factory equipment. Furthermore, an exceedingly comfortable and serviceable shoe is produced 120 since it offers a smooth, non-rubber-foot engaging surface for the foot, and its manufacture is not dependent upon the carefulness 125 and skill of an operator in fitting the filler piece and shank member in proper position on the upper side of the sole. It will be well recognized by those skilled in the art that because of the relatively few major opera- 130

tions necessary in producing the sole and in assembling the constituent parts of the shoe according to this invention, this shoe is peculiarly adapted to meet the needs of an inexpensive outdoor shoe such as is now supplied by the vulcanized rubber soled shoes commonly called "sneakers." These sneaker shoes are not satisfactory in many respects. For example, they give very little service to the wearer in proportion to their cost and are to many people uncomfortable and of a not sufficiently neat appearance. A shoe manufactured as hereinabove set forth, in addition to providing the desired neat appearance and serviceability, gives the proper support to the foot, particularly through the shank portion thereof, and can be worn to the same advantage as a leather shoe.

The shoe and the method of making it, which have been disclosed above, form the subject-matter of a divisional application Serial No. 352,024 and are not claimed herein.

Having thus described my invention, what I claim as new and desire to secure by Letters Patent of the United States is:

1. A vulcanized sole for use in the manufacture of a turned shoe comprising a body portion consisting entirely of vulcanized rubber compound and an upper layer of fabric, there being molded on the upper face of the sole and extending around the margin thereof a flat feather, inside the feather a sewing-rib, inside the rib a gutter, and inside the gutter a filler portion the top of the filler portion being substantially flush with the top of the rib, the gutter being of a width sufficient to provide clearance for the needle of the sewing machine by which the sole is to be attached to the upper of the shoe the bottom of the gutter being located at a level at least as low as that of the feather.

2. A vulcanized sole for use in the manufacture of a turned shoe comprising a body portion consisting entirely of vulcanized rubber compound and an upper layer of fabric, there being molded on the upper face of the sole and extending around the margin thereof a flat feather, inside the feather a sewing-rib, inside the rib a gutter, and inside the gutter a filler portion, the top of the filler portion being substantially flush with

the top of the rib, the gutter being of a width sufficient to provide clearance for the needle of the sewing machine by which the sole is to be attached to the upper of the shoe, the width of the gutter being substantially equal to that of the rib, the bottom of the gutter being substantially flat and located at least as low as that of the feather.

3. As an article of manufacture, a vulcanized rubber sole adapted to constitute the outer tread member of a turn shoe comprising a sole-shaped rubber body portion, a top layer of canvas vulcanized to the rubber body and having its marginal portion raised to form a sewing shoulder along the upper marginal surface of the sole, and an integral layer of fibrous material disposed inside the said sewing shoulder to form the main foot supporting surface of the sole substantially flush with the top of the sewing shoulder with a stitch receiving gutter separating the said fibrous layer and the said sewing shoulder, and a portion extending outwardly from the base of the sewing shoulder, said fibrous layer terminating at the ball line of the sole.

4. As an article of manufacture, a shoe sole comprising a composite sole-shaped blank having a reduced feather portion along its outer margin, a stitch receiving rib against which the shoe upper is sewed extending along the inner margin of the feather portion, a main foot engaging area of substantially the same height as the said stitch receiving rib and separated therefrom by a stitch receiving gutter having its base opposite the base of the stitch receiving rib, and provided with a recess extending through the shank portion of the sole inside the sewing rib and adapted to receive a shank stiffener member.

5. As an article of manufacture, a shoe sole comprising a composite sole-shaped blank molded to provide on its upper marginal surface a sewing rib which projects above the upper surface of the sole inside thereof through the shank and heel seat portion and which is substantially flush with the upper surface of the central portion of the sole through the forepart.

In testimony whereof I have signed my name to this specification.

GEORGE FERGUSON.
